United States Patent Office.

FREDERICK TOWNSEND, OF ALBANY, NEW YORK.

Letters Patent No. 98,317, dated December 28, 1869.

IMPROVED MACHINE FOR QUARRYING AND DRESSING STONE.

The Schedule referred to in these Letters Patent and making part of the same.

To all whom it may concern:

Be it known that I, FREDERICK TOWNSEND, of the city and county of Albany, in the State of New York, have invented a new and improved Machine for Quarrying Stone, and dressing the surfaces of the same; and I do hereby declare that the following is a full, clear, and exact description thereof, reference being had to the accompanying drawings, making part of this specification, in which—

Figure 1 is an elevation of one side of the channeling device, indicated in two positions by the aid of dotted lines.

Figure 2 is a top view of the same parts, indicated by fig. 1.

Similar letters of reference indicate corresponding parts in both figures.

This invention relates to an improvement on devices, which are designed for cutting channels or kerfs into the bed of quarries, preparatory to removing blocks of stone therefrom; also, for chipping and smoothing or dressing the surfaces of stone.

The nature of my invention consists in the application, to the free end of a loaded, vibrating lever, of one or more stone-cutting or dressing chisels, and in giving to said lever strokes, varying in rapidity, by means of a crank-pin, working in a slot made through one arm of said lever, as will be hereinafter explained.

To enable others skilled in the art to understand my invention, I will describe its construction and operation.

In the accompanying drawings—

A represents a disk, which is keyed on one end of a driving-shaft, B, and which has fixed, eccentrically, into its face, a wrist-pin or crank, a.

This pin a works in a slot, which is made through one arm, C, of a strong lever, and causes the lever to vibrate.

The arm D of said lever is loaded, and made of such size and shape as will sustain it against shocks received in a direction transversely, with respect to its length, at the moment of giving the blows.

The shaft E has the loaded lever secured firmly to it, by means of a collar or hub, b, as shown in the drawings.

The chisel, or chisels c, as the case may be, are secured, in any suitable manner, into the loaded end of

the lever-arm D, in such position as will cause the chisels to strike the stone at the angle found best adapted for cutting or dressing.

The drawings represent a single lever, applied upon a rock-shaft, E, and actuated by a crank-pin, playing in a slot in the arm C; but, if desirable, more than one of the loaded chisel-carrying arms D, may be applied upon the rock-shaft E, and operated by a single crank-pin and slotted arm.

In carrying my invention into effect for quarrying stone, I shall mount the devices upon a truck or carriage, provided with feed or propelling-contrivances for moving the chisels along as the work of channeling progresses, and also for vibrating the chisel-carrying arm or arms.

It will be seen, from the above description, and the accompanying drawings, that the loaded chisel-carrying arm receives variable motions; that by the revolution of the crank-pin a, acting upon the arm C, the loaded arm is caused to receive a quick, jerking motion at the terminus of its descending strokes, and at the moment the chisel strikes the object to be cut; and that the movement upward of this arm is at first very quick, and then gradually retarded.

It will also be seen that the action of the wrist-pin a upon the arm C, during the descending, accelerated strokes of the loaded arm D, will greatly add to the force of the blow; and while this is the case, the shocks, incident to the blows given to the chisel or chisels, will not be seriously felt by the machinery, as the radial distance between the fulcrum of said arm D and wrist-pin a rapidly increases immediately after each blow, and allows the arm D to recoil without much resistance.

Having described my invention,

What I claim as new, and desire to secure by Letters Patent, is—

A vibrating loaded arm, carrying one or more stone-cutting or dressing chisels, and receiving its movements from a revolving crank-pin, working in a slotted or forked arm, C, substantially as described.

FREDK. TOWNSEND.
